United States Patent Office.

W. B. C. STIRLING, OF BATAVIA, OHIO, ASSIGNOR TO HIMSELF AND DALE O. COWEN, OF SAME PLACE.

Letters Patent No. 92,550, dated July 13, 1869.

IMPROVED RECORDING-DESK OR TABLE.

The Schedule referred to in these Letters Patent and making part of the same.

To all whom it may concern:

Be it known that I, W. B. C. STIRLING, of Batavia, in the county of Clermont, and State of Ohio, have invented a new and improved Recording-Desk or Table; and I do hereby declare that the following is a full, clear, and exact description thereof, which will enable others skilled in the art to make and use the same, reference being had to the accompanying drawings, forming part of this specification, in which—

Figure 1 is a top view of my improved recording-desk.

Figure 2 is a vertical cross-section of the same, taken through the line x x , fig. 1.

Similar letters of reference indicate corresponding parts.

My invention relates to that class of writing or recording-desks which are provided with a table or leaf, which is made vertically adjustable, in order to bring the pages of the record or other book placed thereon, when open, upon a level with the contiguous upper portion of the desk; and

The invention consists in the combination and arrangement of a right and left-hand screw with the movable apron or leaf, and the frame of the desk, as will be hereinafter fully described.

A is the frame of the desk or table, the top B of which may be made flat or inclined, as may be desired.

The middle part of the forward side of the top or cover B is cut away, as shown in figs. 1 and 2, to form a recess to receive the tables C, which are placed side by side, and at a short distance apart, to accommodate the backs of the books.

The tables C are each made in two parts, c^1 and c^2 . The lower part, c^2 , moves up and down, horizontally, carrying the part c^1 with it.

The part c^1 is hinged, at its forward edge, to the forward edge of the other part c^2 , so the inner end of said part c^1 may be raised or lowered to adjust it to the desired inclination for the record-book.

The parts c^1 are raised and lowered by moving the blocks D, placed between the parts c^1 and c^2 , forward and back, as desired.

To the under side of the part c^2 , is attached a nut, E, having a right or left screw-hole formed through it; and to the cross-bars a^1 of the table-frame A, is attached a similar nut, F, having a left or right screw-hole formed through it.

G is a right-and-left screw, passing through the nuts E and F, and having a hand-wheel, H, attached to its lower end, for convenience in operating it.

It will be observed that while the right-hand screw is being turned in one direction—as, for instance, to elevate the leaf—the left-hand screw must have a reverse movement, whose effect is to likewise aid in elevating the leaf. In other words, while the right-hand screw passes upward through the nut E, the left-hand screw is being withdrawn from the nut F; and, *vice versa*, as the right-hand descends through its nut, the left-hand screw is ascending through the nut E. The effect is that the tables are moved up and down, in adjusting them, with twice the rapidity that would be possible were the screw G swivelled to either the table or frame.

The importance of this construction, however, consists chiefly in allowing the use of a screw of such length that it will project but a few inches below the bottom board of the desk, and thus, at all times, be within easy reach of the writer; while if a screw having a continuous right or left-hand thread were employed, upon lowering the leaf to its fullest extent, the hand-wheel H would be nearly twice the distance below the cross-pieces a^1 , thereby not only detracting from the appearance of the desk as an article of furniture, and also occupying the space required for other uses, but greatly incommoding the writer in operating the screw for raising the leaf.

To the forward side of the table-frame A, is detachably attached a narrow leaf, I, so as to be a continuation of the table-top B, to support the forearm of the writer, when writing upon the lower part of the page.

The leaf I is provided with brackets J, the upper parts of which are provided with hooks, that hook into keepers attached to the frame A, and the lower parts of said brackets rest against the forward side of said frame, to support the said leaf in proper position.

When not required for use, the leaf I may be detached in an instant, and laid aside.

Having thus described my invention,

I claim as new, and desire to secure by Letters Patent—

The combination of the right-and-left screw G, and nuts E F, with the hinged adjustable tables C, and frame A of the table or desk, all constructed substantially as herein shown and described, and for the purpose set forth.

W. B. C. STIRLING.
